C. L. PAINE

MEANS FOR HEATING THE CONTENTS OF VENDING MACHINES

Filed March 30, 1921

FIG. 2

FIG. 1

Inventor
CHARLES L. PAINE.

By

Charles L. Paine

Attorney

Patented July 3, 1923.

1,460,979

UNITED STATES PATENT OFFICE.

CHARLES L. PAINE, OF INDIANAPOLIS, INDIANA.

MEANS FOR HEATING THE CONTENTS OF VENDING MACHINES.

Application filed March 30, 1921. Serial No. 456,889.

To all whom it may concern:

Be it known that I, CHARLES L. PAINE, a citizen of the United States, residing at Indianapolis, in the county of Marion and State of Indiana, have invented certain new and useful Improvements in Means for Heating the Contents of Vending Machines, of which the following is a specification.

This invention relates to means for heating the contents of vending machines and is primarily adapted for use in connection with nut vending machines for the purpose of vending nuts in a heated condition.

The feature of the invention is the provision of an electrical heating device which is placed in the interior of the vending machine and so positioned that a portion thereof will extend over the pocket containing the charge of nuts to be vended so that these nuts will be heated as well as those in the body of the machine.

Other objects and advantages will be hereinafter more fully set forth and pointed out in the accompanying specification.

25 In the accompanying drawings,

Figure 1 is a perspective view of a vending machine with the heating device applied thereto, and

30 Figure 2 is a side elevation of the vending machine partly in section.

Referring to the drawings, 1 indicates the base portion of the vending machine which is preferably constructed of metal and formed in any preferred manner, said base portion supporting a bowl 2 preferably of glass in which the commodity to be vended is placed and when the machine is used for vending peanuts a sliding pocket 3 is positioned below a slot 4 in the top wall 5 of the base, said pocket discharging a measured quantity of the nuts at each operation or outward movement thereof.

In order to maintain the nuts in heated condition at all times, a heating device 6 is positioned within the bowl 2 and rests upon the wall 5 of the base 1, said heating device preferably having a flange 7 at its lower end which fits the diameter of the lower end of the bowl and holds the heating device centrally of the bowl, the flange 7 having a slot 8 which registers with the slot 4. In order to heat the nuts which are contained within the pocket 3 the heating device 6 is so positioned that it will project over the edge of the slot and partially over the nuts within the pocket, consequently the nuts within the

pocket will be heated and maintained in a heated condition the same as the nuts within the lower part of the bowl and surrounding the heating device until such time as the pocket is operated to discharge the nuts therein.

The heating device 6 is connected to a source of electricity through wires 9, the ends of the wires connected with the heating element proper being preferably encased in a tube or cover 10 of suitable length and serving to keep the wires in proper position and to protect them against injury by accumulations of salt and grease which would tend to cause short circuits and thus give rise to fires. The wires are carried to the cover portion 11 of the vending machine and through one wall thereof, and extend to the usual form of socket for connection with an electric circuit. If preferred an electric bulb 12 may be mounted on the cover 11 which receives current from the same source as the heating element. The casing surrounding the resistance element may serve to prevent scorching of the contents of the compartment through direct contact with the said element which is usually made up of small wires that become intensely hot. Other means for the same purpose will occur to those skilled in the art, such as, e. g., an electric current of low voltage through the resistance element.

The heating device may be made of any suitable size and length so as to accommodate the same for heating a greater or less quantity of nuts, and may be constructed to fit in any sized vending machine, a container of desirable form as shown in the drawing, by the use of which only a small quantity of nuts near the bottom will be heated. Those in the upper enlarged portion will receive some heat and be warmed to an increasing degree as they approach the bottom of the machine and are progressively removed therefrom. Preferably the heating element is made in the form shown with an apertured plate fitting within the lower portion of the storage compartment and an upwardly projecting portion centrally located in the compartment. In this way the plate will keep its proper position with its aperture in register with the delivery pocket and the vertical heating device will have the best effect with the least waste of heat. The nuts or other materials surrounding the device 6 act to some extent as a heat insulator

to prevent undue radiation to and through the wall of the machine. I may use storage compartments of various forms and may modify the device in other respects, the true scope of the invention being indicated by the appended claims. While specific terms are used in the claims it is not desired, for example, to limit the machine to the heating of peanuts since popcorn, salted or un-salted peanuts, chestnuts, chinkapins and other articles or materials whose flavor is improved by heating may be vended by a machine so heated. Therefore it will be seen that such terms are used for purposes of description and not for limitation.

Having thus fully described my said invention, what I claim as new and desire to secure by Letters Patent, is:

1. A vending machine for peanuts and the like comprising a heat-generating device enclosed in a protecting element and positioned in contact with the contents of the machine, whereby such contents may be maintained in heated condition without scorching.

2. A vending machine for combustible products comprising a storage compartment, means for withdrawing such products in predetermined quantities, and an electrical heating device positioned within the storage compartment for maintaining the products in heated condition and comprising a protecting casing to prevent the scorching of said contents, substantially as set forth.

3. The combination with a vending machine having a nut receiving bowl and a nut receiving pocket at a point below the bowl, of a heating device in the bowl for heating the contents of said bowl, said heating device projecting partially over said pocket to engage the contents thereof for heating the same, substantially as set forth.

4. The combination with a nut vending machine including a base portion and a bowl portion, of a heating device positioned within said bowl portion, having a flange adapted to rest upon parts of the base portion and hold the heating device in spaced relation with the bowl.

5. In combination, a vending machine for salted peanuts and the like, said machine having a storage compartment, an electric heater therefor comprising a cylindrical casing containing a resistance element and standing in the compartment, an elongated tubular protector of grease-excluding material extending upward from said casing, wires leading from the resistance element through said protector and out of the compartment, said protector safeguarding the wires against the action of grease and salt, substantially as set forth.

6. A vending machine having a storage compartment and an outlet therefrom, a removable cover for the storage compart-

ment, an electric heating device in the storage compartment adjacent the outlet, said cover having an aperture, a lamp carried by the cover, electric wires passing through said aperture to the heating device and the lamp and a grease-proof casing extending upward from said heating device and surrounding the wires connected thereto, substantially as set forth.

7. A vending machine for peanuts and the like having a storage compartment with a transparent wall, a vertically-extending heating device centrally arranged in the compartment and forming therewith an annular space whereby articles occupying said space will be heated and will serve to prevent radiation of heat to and through said wall, substantially as set forth.

8. In a peanut warmer, a receptacle for nuts having a measuring pocket beneath the receptacle and an electric heating device comprising a plate resting on the bottom of the receptacle and extending partially over the pocket to warm its contents, substantially as set forth.

9. In a vending machine for food products a storage compartment, means to discharge said products in uniform quantities, and electrical heating means held in stationary position in said compartment said heating means being provided with a protector to prevent scorching of said products.

10. The combination with a vending machine having a nut receiving bowl and a nut dispensing and measuring pocket at a point below the bowl, of a heating device in the bowl for heating the contents of said bowl, said heating device disposed adjacent said pocket to be in proximity to the contents thereof for maintaining the same in a heated condition, substantially as set forth.

11. In a vending machine for food products a storage compartment, means to discharge said products in uniform quantities, electrical heating means disposed adjacent said first named means and provided with a protector to prevent scorching of said products, substantially as set forth.

12. In a vending machine for food products a storage compartment, means to discharge said products in uniform quantities, electrical heating means disposed adjacent the discharging means, and having provision to prevent scorching of said products, substantially as set forth.

In witness whereof, I have hereunto set my hand and seal at Indianapolis, Indiana, this 22nd day of March, A. D., nineteen hundred and twenty-one.

CHARLES L. PAIN. [L.S.]
